UNITED STATES PATENT OFFICE

164,740

DISHWASHER CABINET

Jacques Stanitz, Warren, Ohio, assignor to Mullins Manufacturing Corporation, Salem, Ohio, a corporation of New York

Application April 12, 1950, Serial No. 9,163

Term of patent 14 years

(Cl. D49—1)

To all whom it may concern:

Be it known that I, Jacques Stanitz, a citizen of the United States, residing at Warren, in the county of Trumbull and State of Ohio, have invented a new, original, and ornamental Design for a Dishwasher Cabinet, of which the following is a specification, reference being had to the accompanying drawings, forming part thereof.

Figure 1 is a perspective view of a dishwasher cabinet, showing my new design;

Fig. 2 is a plan view thereof; and

Fig. 3 is an end view thereof.

The rear of the cabinet, not shown, presents substantially a plane surface. The dominant features of my design are shown by means of full lines in the drawings.

I claim:

The ornamental design for a dishwasher cabinet, substantially as shown and described.

JACQUES STANITZ.
